ELECTRICAL APPARATUS.

Application filed October 27, 1921. Serial No. 510,916.

This invention relates to electrical apparatus, such as rectifiers, of the type having opposed electrodes between which current flows by gaseous conduction, and more particularly to apparatus having electrodes of the low temperature type, that is, of the type which operate below thermionic emission temperature in contradistinction to the incandescent type. A rectifier of the general class to which the present invention relates is disclosed in the copending application of Smith, Serial No. 415,536, filed October 8, 1920.

Apparatus of this type operate at relatively high potentials compared to the operating potentials for thermionic tubes, and the consequent positive ion bombardment of the cathode surface, as well as other exposed surfaces in the tube, gives rise to problems which are ordinarily not experienced in thermionic tubes. One such problem is that of preventing the gas molecules from being permanently entrapped by the aforesaid bombardment of positive ions, thereby reducing the gas pressure below that required for normal operation of the tube. Such occlusion will ordinarily take place in tubes of the type referred to, both in the solid metal of the electrodes (principally the cathode) and also in the walls of the glass tube and other surfaces exposed to the bombardment.

In one aspect this invention involves confining said bombardment to a restricted area, preferably the active surface of the cathode, and in another aspect the invention involves forming the bombarded area of material which, instead of entrapping the gas, permits the gas to escape. This is preferably accomplished by making the cathode surface, or other bombarded area, of material which is porous, that is, constituted to permit the gas to escape. While there are various ways of preventing the gas from being entrapped, as disclosed in subsequent applications of said Smith, the specific way herein-after described is to make the bombarded surface of carbon.

In a more specific aspect this invention involves apparatus in which the spacing between the electrodes and the gas pressure are correlated to prevent substantial conduction along the shortest paths between the electrodes at potentials which produce gaseous

conduction along longer paths between the electrodes, in combination with means as aforesaid for preventing the gas from being entrapped, whereby the gas pressure is maintained in proper relation to the lengths of said paths. Thus the invention affords a solution for the problem, which is peculiar to tubes of the type disclosed in said Smith application, of keeping the pressure sufficiently low to prevent conduction along the short paths while preventing the pressure from becoming too low for conduction along the longer paths, at least at the rated voltage of the tube.

The apparatus disclosed in said Smith application comprises two electrodes immersed in a gas and having their active surfaces spaced apart a distance which is of the order of magnitude of the mean free path of electrons through the gas. Electrodes constructed and arranged in this manner if included in an electric circuit provide a gap which is normally insulating even when subjected to high potential differences. It is possible, however, by lengthening or shortening the path of electrons in certain directions to vary conduction through the gas and cause complete rectification if so desired.

As conduction between electrodes of this character takes place by virtue of ionization of the gas rather than by thermionic conduction in a vacuum or by arcing between the electrodes, it is highly desirable that the characteristics of the gaseous medium in which the electrodes are immersed shall remain substantially constant or in any event that the gaseous medium shall not be absorbed or disappear during the continued operation of the gap.

I have discovered that if carbon electrodes are immersed in a chemically inactive gas that gaps of this character may be operated for long continued periods of time without any substantial change in gas pressure. I have also found it to be desirable that an inert gas, such as helium in a substantially pure state be employed in connection with these carbon electrodes.

In addition to providing carbon electrodes immersed in a monatomic gas, it is desirable that the electrodes shall be free from occluded gases and to this end the electrodes prior to immersion in the operating gas may

be freed of gases which may be contained therein by heating in a vacuum for a sufficient length of time to drive off such gases.

The accompanying drawing illustrates a tube embodying the new features of the present invention, this tube having two carbon electrodes of cylindrical form arranged concentrically with respect to one another.

The specific form of the invention shown in the drawing comprises a hermetically sealed receptacle 10 filled with helium. Enclosed within the receptacle and immersed in the helium are two cooperating electrodes 12 and 14 of carbon. The inner electrode 15 is held at opposite ends by steel cups 16 and 18 which are tied together to clamp the electrode in place by a rod 20. The lower cup 18 has a reduced portion 22 received within the electrode member 14 and a larger skirt portion 24 approximating the diameter of the outer electrode which serves as a shield as hereinafter pointed out. The cup 18 is supported within the receptacle 10 by members 25 which connect the inner 25 face of the portion 24 with the end 26 of the receptacle. The outer and cooperating carbon electrode 12 is enclosed within a cup comprising steel rings 28 and 29 having a band of non-magnetic material 30 interposed therebetween and welded thereto in any suitable manner. The carbon electrode cylinder may be conveniently held in the enclosing cup by a plurality of small pins, as indicated at 32, and an inturned flange 35 formed on the ring 29. The outer cup member is connected to the opposite end of the receptacle 10 by supports 34, as indicated. By virtue of this construction the inner and outer electrode cylinders are securely retained in concentric relation with respect to one another. A magnetic field is impressed upon the space separating the electrodes by a permanent magnet, indicated generally at 40, the field being localized in the space 40 opposite the band 30 of non-magnetic material. The inner and outer electrode members are connected with leading-in wires 42 and 44 which may be connected into any desired form of circuit. If a tube of this 45 form is embodied in a circuit including a source of alternating current and with a magnetic field of correct strength, conduction will take place freely through the gaseous medium when the outer electrode is negative and the tube will act as an insulating medium against conduction in the opposite direction when the inner electrode is negative, thus causing the tube to function as a rectifier. It will be obvious that a tube 50 of this form may be included in any desired form of circuit and that by a proper design of the tube and the strength of the impressed magnetic field the tube may be caused to function as a modulator of electric energy 55 as well as a rectifier.

While the theory of operation by which the particular apparatus herein illustrated functions as a rectifier is disclosed in said Smith application and while the present invention is in no wise dependent upon the use of a magnetic field, it may be here noted that while the field acts during both half-cycles of potential it is effective to permit conduction only during the half-cycles when the outer electrode is negative for the reason that the electrodes are of different size and curvature. Electrons traveling from the outer electrode under the influence of the field traverse paths sufficiently long to produce ionization sufficient to initiate conduction while electrons traveling from the inner electrode under the influence of the field do not traverse paths long enough to produce ionization sufficient to initiate conduction.

It has been explained heretofore that for best results the carbon electrodes should be substantially free of gas and the gas in which the electrodes are immersed should be helium, neon, or a gas of similar characteristics freed from any substantial quantity of impurities in the shape of active gases. Furthermore the carbon electrodes should preferably be in a pure state, that is free from admixture with clay or similar impurities, although the form of the carbon may be either the soft graphite of commerce or the harder dense form of carbon commonly employed as arc electrodes.

In connection with this invention it should be understood by those skilled in the art that these carbon electrodes are immersed in a gas through which conduction takes place by virtue of ionization of the gas. In this respect the present form of apparatus is to be clearly distinguished from apparatus whose conducting properties depend upon the emission of electrons from an incandescent filament or similar member or an apparatus having two electrodes between which an electric arc is formed. In the present form of apparatus neither the cathode nor the anode is operated at incandescence.

While it is preferred to employ the specific construction and arrangement of parts shown and described it will be understood that this construction and arrangement is not essential except so far as specified in the claims and may be changed or modified without departing from the broader features of the invention.

The radial surface of part 24 which extends outwardly from the diameter of electrode 14 to the diameter of electrode 12 intermediate the reentrant stem 26 and the space between the two electrodes where the electrical discharge occurs, protects that portion of the tube where the conductor 22 enters the tube from the electrical discharge

and the radiation of light and heat therefrom. By making the part 28 nonintegral with either of the electrodes it may be formed of different material and the parts 5 may be constructed more efficiently. By extending the conducting shield 18 into closely spaced relationship to the wall of the tube the gaseous discharge is effectually confined to the interior of the hollow electrode.

10 In a generic sense, the term hollow cathode includes a cathode whose active surface only partially surrounds a gaseous medium so that the medium immediately adjacent the active surface is more or less pocketed 15 or confined.

From the foregoing it will be evident that the shield 16 extends lengthwise or longitudinally of the anode 14 along a gap between the depending portion of the shield 20 and the tube 10, the radial dimension of the gap between the depending portion of the shield and the tube 10 normal to the shield being substantially confined to the mean free path of the electrons in the gas, there- 25 by more effectually confining the discharge to the interior of the hollow cathode.

The invention having been described, what is claimed is:

1. Electrical apparatus comprising spaced 30 electrodes in a sealed container containing gas, the shortest gap between the electrodes and the gas pressure being correlated to prevent substantial conduction across said gap at potentials which produce gaseous con- 35 duction along longer paths between the electrodes, and that portion of the electrode which is subjected to bombardment of positive ions being formed of material suffi- 40 ciently porous not to entrap said gas in sub- 45 stantial degree, whereby the gas pressure is maintained in proper relation to the length of said gap.

2. Electrical apparatus comprising spaced 45 cathode and anode in a sealed container containing gas, the shortest gap between the electrodes and the gas pressure being correlated to prevent substantial conduction across said gap at potentials which produce gaseous conduction along longer paths be- 50 tween the electrodes, and the active surface of the cathode being formed of material constituted so as not to entrap said gas in substantial degree, whereby the gas pressure is maintained in proper relation to the 55 length of said gap.

3. Electrical apparatus comprising a sealed container containing gas, a hollow cathode and an anode presented to the interior surface of the cathode, the cathode 60 operating below the temperature at which the discharge is dependent upon thermionic emission, said surface being formed of ma- 65 terial constituted to prevent permanent entrapment of said gas in substantial degree.

4. Electrical apparatus comprising a

sealed container containing gas, a hollow cathode and an anode presented to the interior surface of the cathode, the cathode operating below the temperature at which the discharge is dependent upon thermionic 70 emission, the apparatus being constructed and arranged to confine the bombardment of positive ions substantially to said surface, and said surface being formed of material constituted to prevent permanent entrap- 75 ment of said gas in substantial degree.

5. Electrical apparatus comprising a sealed container containing gas, a hollow cathode of the low temperature type, and an anode presented to the interior surface of said 80 cathode, said surface being formed of material sufficiently porous at low temperatures to release gas carried into the surface by positive ion bombardment produced by potentials high enough to effect gaseous con- 85 duction between low temperature electrodes.

6. Electrical apparatus comprising spaced 90 cathode and anode of the low temperature type in a sealed container containing gas, the active surface of the cathode being formed of material constituted to prevent permanent entrapment of gas carried into the surface by positive ion bombardment produced by potentials high enough to effect gaseous con- 95 duction between low temperature electrodes.

7. Electrical apparatus comprising spaced 100 cathode and anode of the low temperature type in a sealed container containing gas, the active surface of the cathode being formed of material sufficiently porous at low temper- 105 atures to release gas carried into the surface by positive ion bombardment produced by potentials high enough to effect gaseous conduction between low temperature electrodes, and means for confining the positive ion bombardment substantially to said active surface.

8. A gaseous conduction tube containing 110 gas and having a reentrant stem, a tubular electrode having one end directed toward said stem, a member having an electrode surface presented to the interior of said tubular electrode, a conductor extending through said stem for conducting current to said surface, and another member having a shielding 115 surface extending transversely of the axis of said tubular electrode between said end of the tubular electrode and said reentrant stem, said shielding surface extending outwardly from a diameter substantially con- 120 fined to that of said electrode surface to a diameter at least substantially as great as that of the opening in the adjacent end of the tubular electrode and extending longitudinally of said member along a gap sub- 125 stantially confined to the mean free path of electrons in the gas.

9. A gaseous conduction tube containing 130 gas and having a reentrant stem, a hollow cathode having one end directed toward said

- stem, a member having an electrode surface presented to the interior of said hollow cathode, a conductor extending through said stem for conducting current to said surface, and
- 5 another member having an annular metallic surface presented to the space between said hollow cathode and said electrode surface intermediate said stem and said end of the
- 10 hollow cathode, said annular surface having a radial dimension at least approximately as great as the difference in diameter between said hollow cathode and said electrode surface and being insulated from one of said electrodes by a gap substantially confined to
- 15 the mean free path of electrons in the gas.

10. A gaseous conduction tube containing

gas and having a reentrant stem, a cathode opposite said stem, intermediate said stem and cathode a member having an electrode surface presented to said cathode, and another member intermediate said stem and electrode surface, the latter member having a surface extending outwardly from a diameter substantially confined to that of said electrode surface to a diameter at least substantially as great as that of said cathode and extending along a gap whose dimension normal to the surface is substantially confined to the mean free path of electrons in the gas.
